TOILET SEAT COVER

Charles K. Arter, Jr., Shaker Heights, and Samuel Peskind, Cleveland, Ohio

Application September 12, 1941, Serial No. 410,572

2 Claims. Cl. (4-243)

This invention relates to improvements in toilet seat covers, that is to say, covers formed of thin sheet material such as paper and adapted to be used once and thrown away. One of the objects of the invention is the provision of a cover for the purpose indicated which shall be of low cost and adapted to rapid production in quantities.

Another object is the provision of a cover of this character which may be temporarily attached to the toilet seat without fastenings of any kind other than small patches of adhesive of a character such that it may be caused to adhere to a surface by the application of pressure.

Other objects and features of novelty will appear as we proceed with the description of those embodiments of the invention which, for the purposes of the present application, we have illustrated in the accompanying drawing, in which

Fig. 1 is a plan view of one embodiment of the invention.

Fig. 2 is a fragmental cross-section on a larger scale, the view being taken substantially on the line 2-2 of Fig. 1.

Fig. 3 is a plan view of a portion of a web comprising a multiplicity of units which may be rolled up, and from which the units may be removed one at a time as needed.

Fig. 4 is a detail sectional view on a larger scale, the view being taken substantially on the line 4-4 of Fig. 3.

Fig. 5 is a plan view of another modification of the invention.

Fig. 6 is a large scale sectional view taken substantially on the line 6-6 of Fig. 5.

Fig. 7 is a view similar to Fig. 1, showing still another modification, and

Fig. 8 is a large scale fragmental sectional view taken substantially on the line 8-8 of Fig. 7.

Referring first to Figs. 1 and 2, 10 is a sheet of thin flexible material, preferably paper, which is adapted to fully cover a toilet seat, the latter being indicated by broken lines in Fig. 1 at 11. The sheet 10 is provided with a large opening 12 conforming more or less with the opening in the seat, and on either side of opening 11 there is a series of openings 13, in this case shown as spaced slots. These openings could be of round or other shape and a continuous slot can be substituted for the spaced slots illustrated.

On the upper surface of the sheet a strip 14 of gummed paper or the like is laid face down covering the slots 13, and is caused to adhere to the sheet by pressure. On the under side of the sheet another strip 15 is caused to underlie the

openings 13 and is held in place by pressure which causes the adhesive on the strip 14 within the openings 13 to adhere to the strip 15. The make-up of the strip 14 and/or the properties of the adhesive are such that there is some physical, chemical or mechanical bonding of the adhesive to its backing which is much stronger than the connection between the adhesive and the strip 14, or anything else with which the adhesive may be caused to contact. In this respect the strips 14 are similar to a commercial product known as Scotch tape. The strips 15 are employed merely as temporary shields for the adhesive, which would otherwise be exposed through the openings 13 and might cause the sheets to stick together when folded up to form packages suitable for dispensing in a slot machine. As a material for the strips 15 we select a paper or like material which is relatively non-porous and has a smooth and comparatively hard surface. Cellophane has been found to be well adapted to the purpose.

When a sheet is to be used the strips 15 are pulled off and the sheet is placed over the seat 11 and pressed down, with the result that the adhesive exposed through the openings 13 clings to the seat. The cover sheet 10 therefore is held against accidental displacement when in use. However, the adherence of the adhesive to the surface of the seat is comparatively weak and the cover may be stripped from the seat without difficulty and without leaving any appreciable part of the adhesive thereon.

The modification shown in Figs. 3 and 4 is similar to the preferred form above described. In this instance we start with a continuous web which is divided at regular intervals by perforations 16 into a multiplicity of sheets 10a. Each of these sheets has openings 12a and 13a which may be identical with the corresponding openings of Fig. 1. For convenience in manufacture, however, the strips 14a are applied as continuous tapes, and the pressure necessary to unite them with the sheets may be supplied through rollers, as will be obvious. The perforations 16 must, of course, run through the tapes as well as through the web proper. In this form of the invention the web is made up in rolls, but as the openings 13a of one sheet will always overlie the backs of the strips 14a of another sheet, these backs being relatively resistant to the adhesive, no difficulty arises with respect to one sheet sticking to another.

Referring again to Figs. 1 and 2, attention is called to the fact that if desired the form of the

invention there illustrated, like that of Figs. 3 and 4, can be made in a continuous web, the strips 14 and 15 being then applied as continuous tapes and the units being separated by scored lines which cut the tapes as well as the web.

In Figs. 5 and 6 there is shown a modification in which a sheet of paper or the like 10b has a large opening 12b but no small openings corresponding to the openings 13 and 13a of the previously described forms of the invention. The sheet is caused to adhere temporarily to the seat by means of a gummed strip 18, the back of which engages the bottom surface of the sheet 10b. This strip is held in place by two other gummed strips 19 and 20 arranged on either side of the strip 18 and overlapping the side edges of that strip more or less. Strips 19 and 20 have their gummed faces uppermost so that they adhere to the sheet and to the strip 18, leaving a narrow length of adhesive on the latter strip exposed, as indicated in Fig. 6. The strips 19, having appreciable thickness, tend to hold the exposed gummed surface away from any other surface except when substantial pressure is applied. In use these exposed portions of strip 18 cling to the seat surface and prevent accidental movement of the cover, but when the latter is to be discarded it may be readily stripped from the seat and will leave behind no appreciable amount of adhesive.

The modification in Figs. 7 and 8 shows the invention in its simplest form. Here the sheet 10c is merely coated on its under surface with small areas of adhesive 21, which may or may not be elongated strips as shown. In this case the sheet 10c itself is united with the adhesive by a strong bond just as is the tape in the previously described forms of the invention, and the material of the sheet is preferably a non-porous one having a hard and smooth surface, 40

like the strips 15 of Figs. 1 and 2, so that when the sheets are stacked or folded they will not adhere to each other. It will be obvious also that, if desired, this unit may be made in a continuous web in the manner illustrated in Fig. 3.

In the foregoing description we have necessarily gone somewhat into detail in order to explain fully the particular embodiments of the invention herein illustrated, but we desire it to be understood that such detail disclosures are not to be construed as amounting to limitations except as they may be included in the appended claims.

Having thus described our invention, we claim:

15 1. In a toilet seat cover, a sheet of paper for covering the top of the seat, said sheet having openings therethrough in positions to meet the upper surface of the seat when the cover is laid thereupon, and gummed tape adherently attached to the upper side of the sheet overlying the said openings and exposed to the upper surface of the seat through said openings when the cover is laid thereupon.

20 2. In a toilet seat cover, a sheet of paper for covering the top of the seat, said sheet having openings therethrough in positions to meet the upper surface of the seat when the cover is laid thereupon, gummed tape adherently attached to the upper side of the sheet overlying the said 25 openings and exposed to the surface of the seat through said openings when the cover is laid thereupon, and strips of glossy material laid beneath said openings and removably attached to the sheet by the adhesive on the tape within said openings, said glossy material adapted to screen the adhesive within the openings until the glossy material is removed preparatory to the attachment of the cover to the seat.
